Primary Examiner—Lucy Lieberman(74) *Attorney, Agent, or Firm*—Lars S. Johnson**(57) CLAIM**

The ornamental design for a bottle, as shown and described.

DESCRIPTION

FIG. 1 is a perspective view of a bottle showing our new design;

FIG. 2 is a front elevation of the bottle, the rear elevation is the same except for the conventional screw threading on the neck;

FIG. 3 is a left side elevation, the right side elevation is the same except for the conventional screw threading on the neck;

FIG. 4 is a top view the bottle depicted in FIG. 2;

FIG. 5 is a bottom view of the bottle depicted FIG. 2;

FIG. 6 is a perspective view of a second embodiment of a bottle as depicted in FIG. 1;

FIG. 7 is a front elevation of the second embodiment, the rear elevation is the same except for the conventional screw threading on the neck;

FIG. 8 is a left side elevation of the second embodiment, the right side elevation is the same except for the conventional screw threading on the neck; and,

FIG. 9 is a top view of the bottle depicted in FIG. 7.

The bottom of the second embodiment is the same as the bottom of the first embodiment.
